(57) **CLAIM**

The ornamental design for an exercise stand, as shown and described.

DESCRIPTION

FIG. 1 is a top, front, right perspective view of my new design with additional selected features disclaimed;

FIG. 2 is a top, front, left perspective view thereof;

FIG. 3 is a left side view thereof;

FIG. 4 is a right side view thereof;

FIG. 5 is a front view thereof;

FIG. 6 is a rear thereof;

FIG. 7 is a top view thereof; and,

FIG. 8 is a top, front, right perspective view of the design in FIGS. 1-7 showing additional example environment.

The broken lines depicting the remainder of the exercise stand show features that form no part of the claimed design.

1 Claim, 8 Drawing Sheets# US D854,637 S
